(57) **CLAIM**

The ornamental design for a measuring wheel, as shown and described.

DESCRIPTION

FIG. 1 is a perspective view of a measuring wheel with blade extended in accordance with a first embodiment of the present invention;

FIG. 2 is a bottom view of the measuring wheel of FIG. 1;
FIG. 3 is a top view of the measuring wheel of FIG. 1;
FIG. 4 is a front view of the measuring wheel of FIG. 1;
FIG. 5 is a rear view of the measuring wheel of FIG. 1;
FIG. 6 is a left side view of the measuring wheel of FIG. 1;
and,
FIG. 7 is a right side view of the measuring wheel of FIG. 1.

The broken lines of FIGS. 1-7 are illustrative of the visible environmental structure of the measuring wheel and form no part of the claimed design.

1 Claim, 6 Drawing Sheets
